UNITED STATES PATENT OFFICE.

HENRY F. NELSON, OF ANGOLA, LOUISIANA, ASSIGNOR OF ONE-HALF TO WILLIAM WALLACE PECUE, OF ANGOLA, LOUISIANA, AND ONE-HALF TO WILLIAM T. HODGE, OF BAYOU SARA, LOUISIANA.

RAIL-JOINT.

1,109,780.

Specification of Letters Patent.

Patented Sept. 8, 1914.

Application filed December 3, 1913. Serial No. 804,498.

To all whom it may concern:

Be it known that I, HENRY F. NELSON, a citizen of the United States, residing at Angola, in the parish of West Feliciana 5 and State of Louisiana, have invented a new and useful Rail-Joint, of which the following is a specification.

The present invention appertains to rail joints and aims primarily to provide a novel 10 and improved device of that character.

It is the object of the present invention to provide a rail joint embodying a pair of side members adapted to clamp the rail ends therebetween, and having interengageable 15 portions for locking the side members together.

Another object of the present invention is to provide a device of the nature indicated 20 wherein the side or clamp members are provided with such peculiar interengageable portions below the rails, as to cause the side members to be moved together, upon pressure being given to bear upon the rail ends, in order that the rail ends will be 25 tightly clamped or gripped when a train is traversing the track.

A further object of the present invention is to provide a device of the character specified which will be comparatively simple, 30 substantial, durable and inexpensive in construction, as well as being convenient, practical, safe and efficient in its use.

With the foregoing general objects outlined, and with other objects in view, which 35 will be apparent as the nature of the invention is better understood, the present invention resides in the combination and arrangement of parts and in the details of construction hereinafter described and claimed, it 40 being understood that changes in the precise embodiment of the invention herein disclosed, can be made within the scope of what is claimed, without departing from the spirit of the invention.

The invention has been illustrated in its preferred embodiment in the accompanying drawing, wherein:—

Figure 1 is a plan view of the rail joint, one rail end and the corresponding portion 50 of the fish plates or jaws being shown in section. Fig. 2 is a cross section of the joint, taken on the line 2—2 of Fig. 1. Fig. 3 is an end view of the side or clamping members in slightly separated positions, illus-

trating the manner of moving the said members to and from each other. 55

In carrying out the present invention, the two members of the present device embody the respective base portions 1 and 1' having the respective upstanding fish plates or 60 clamping jaws 2 and 2'. The base portions 1 and 1' are adapted to rest upon the ties and are adapted to receive thereon, the edge portions of the rail flanges as clearly seen in Fig. 2, while the fish plates or jaws 2 and 65 2' are adapted to fit against the webs of the rails R between the base flanges and heads or balls of the rails.

The fish plate or jaw 2 is provided with the inner sockets 3 adapted to register with 70 the openings or slots O of the rails, while the other fish plate or jaw 2' is provided with inner lugs or dowels 4 adapted to pass through the slots O of the rails R to engage the sockets 3. 75

The adjoining edges of the base portions 1 and 1' are spaced apart underneath the base flanges of the rails and are provided with the overlapping tongues or portions 5 and 6 respectively. The tongue 5 of the base portion 1', is preferably flush with the upper face of the said base portion, while the tongue 6 of the base portion 1 is preferably flush with the bottom or lower face of the said base portion 1, the tongues 5 and 6 80 having their adjoining faces beveled from their free edges to their basal edges, or to the edges of the base portions 1 and 1' respectively. The adjoining beveled faces of the tongues 5 and 6 are adapted to interengage, and are preferably cut laterally on compound curves, as clearly seen in Figs. 2 and 3. 85

To assemble the clamp or side members with the rails, the clamp members are placed 90 over the opposite sides of the rail ends, the rail ends being raised. Then, by overlapping the tongues 5 and 6, the fish plates or jaws 2 and 2' may be swung together against the webs of the rails, the dowels 4 being 95 adapted to pass through the openings O in the rails R to engage the sockets 3, which will lock the clamp members against longitudinal movement with respect to one another. In this manner, the rail ends are 100 anchored loosely within the clamp members, the elongated openings or slots O of the rail webs permitting the rails to slide longi- 105

tudinally due to expansion and contraction of the rails under atmospheric changes. The base flanges of the rails are adapted to rest upon the upper tongue 5 and the lower bevelled face of the tongue 5 resting upon the upper bevelled face of the tongue 6, will cause the clamp or side members to be moved toward each other, upon pressure being applied to the rail ends. Thus, when a train 10 traverses the track, the joints will be tightened under the weight of the train, in order that the train may safely pass over the joints without accident.

The adjoining faces of the tongues 5 and 15 6 being curved as above described, will provide longitudinal rounded contacting portions between the tongues, which will reduce friction, in order that the downward pressure upon the tongue 5 will cause the 20 tongues to overlap further under the pressure, so as to clamp the fish plates or jaws 2-2' against the rails. The peculiar formation of the adjoining faces of the tongues 5-6 will also permit the clamp members to 25 be interlocked and unlocked in a convenient and efficient manner, it being observed that 30 when the tongues are overlapped as illustrated in Fig. 2, the side members of the device will be locked against separation transversely or laterally, the dowels 4 in 35 engaging the sockets 3 also locking the said members against longitudinal movement. To release the clamp members, it is merely necessary to raise the rail ends, in order 40 that the side members may first be swung apart to release the rail webs, and which will in turn permit the tongues to be released from each other and from under the base flanges of the rails.

40 The present joint will be an effective one, the parts thereof not being capable of displacement or dislodgment accidentally. The parts of the joint cannot work loose, as would be liable to cause wreckage or other

accidents, it being noted that the parts are 45 not only interlocked, but are so interlocked as to be tightened upon pressure being applied to the rail ends.

The parts of the device are preferably 50 constructed of steel, or other suitable material may be employed, in order that the device may withstand the hammering and concussions to which it is subjected in use.

Having thus described the invention, what 55 is claimed as new is:—

1. In a rail joint, clamp members adapted to receive the rail ends, and having tongues arranged to overlap beneath the rails, the adjoining faces of the tongues being curved laterally on compound curves so as to have 60 longitudinal rounded contacting portions, whereby the clamp members are moved together under pressure upon the rail ends and whereby the clamp members are adapted to be swung together and apart laterally. 65

2. In a rail joint, clamp members each embodying a base portion having an up-standing web engaging jaw, the adjoining edges of the base portions having upper and lower overlapping tongues, the adjoining 70 faces of the tongues being curved laterally on compound curves so as to have longitudinal rounded contacting portions, whereby the clamp members are moved together under pressure upon the rail ends, and 75 whereby the clamp members are adapted to be swung together and apart laterally, the jaws having interchangeable dowels and sockets, and the dowels being engageable through the apertures in the rail webs. 80

In testimony that I claim the foregoing as my own, I have hereto affixed my signature in the presence of two witnesses.

HENRY F. NELSON.
